Primary Examiner — Mark A Goodwin(74) *Attorney, Agent, or Firm* — Burr & Forman, LLP(57) **CLAIM**

The ornamental design for a power grinder, as shown and described.

DESCRIPTION

FIG. 1 is a perspective view of a power grinder in accordance with the present invention;

FIG. 2 is a front view of the power grinder of FIG. 1;

FIG. 3 is a rear view of the power grinder of FIG. 1;

FIG. 4 is a top view of the power grinder of FIG. 1;

FIG. 5 is a bottom view of the power grinder of FIG. 1;

FIG. 6 is a left side view of the power grinder of FIG. 1; and,

FIG. 7 is a right side view of the power grinder of FIG. 1.

The broken line showing of various components is included for the purpose of illustrating portions of the power grinder that form no part of the claimed design.

1 Claim, 7 Drawing Sheets(56)
